UNITED STATES PATENT OFFICE.

JOHN J. REED, OF LYONS, IOWA.

IMPROVEMENT IN CAN-OPENERS.

Specification forming part of Letters Patent No. 137,149, dated March 25, 1873.

To all whom it may concern:

Be it known that I, JOHN J. REED, of Lyons, in the county of Clinton and State of Iowa, have invented a new and useful Improvement in Can-Opener, of which the following is a specification:

The figure is a side view of my improved can-opener.

My invention has for its object to furnish an improved knife for opening tin cans, such as fruit-cans, oyster-cans, &c., which shall be simple in construction, convenient in use, and effective in operation; and it consists in the can-opener, the blade of which is made with a shoulder and curved edge, as hereinafter more fully described.

A represents the handle, to which is attached the shank or tang of the blade B. The blade B is made with a straight back and curved edge, as shown in the figure. The blade B is made with a sharp point, and upon its back, close to its point, is formed a shoulder or notch, b', as shown in the figure. The shoulder b' is intended to keep the blade from being pushed in too far when forcing the point into the can, and also to prevent the

blade from sliding forward while making the cut.

In using the opener the point of the blade B is forced into the can until stopped by the shoulder b'. The handle A is then pressed downward, which causes the blade to cut its way through the tin for its whole length. The point of the blade B is then inserted at one end of the cut and a cross cut is made. The point of the blade is then inserted in the end of the cross-cut, and a third-cut is made. The piece thus cut out upon three sides can then be turned back with the point of the blade and the can is opened. The can-opener thus operates as a lever, the shoulder b' operating as a fulcrum.

Having thus described my invention, I claim as new and desire to secure by Letters Patent—

A can-opener, A B b', constructed as described, with a curve or edge of blade, and a rectangular notch on back near the point, as and for the purpose described.
